CLAIM

The ornamental design for a portable stove, as shown and described.

DESCRIPTION

FIG. 1 is a perspective view of a portable stove, showing my new design;

FIG. 2 is another perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof; and,

FIG. 9 is an operational perspective view of the portable stove showing that a support of the portable stove is folded. The broken lines shown in the drawings depict portions of the article that form no part of the claimed design.

1 Claim, 9 Drawing Sheets
